UNITED STATES PATENT OFFICE.

EMILE PRAT, OF PARIS, FRANCE, ASSIGNOR TO SOCIÉTÉ DES CHEMINÉES LOUIS PRAT
À TIRAGE INDUIT, OF PARIS, FRANCE.

CHIMNEY DRAFT DEVICE WITH TWO FANS.

Application filed April 27, 1921. Serial No. 464,950.

To all whom it may concern:

Be it known that I, EMILE PRAT, a citizen of the Republic of France, residing at Paris, France, 64 Rue de Miromesnil, have invented 5 certain new and useful Improvements in Chimney Draft Devices with Two Fans, of which the following is a specification.

My invention relates to induced draft devices of the type described in my pending 10 application Serial No. 370,860 filed April 2nd, 1920, in which a fan is arranged wholly inside the chimney and is stream-lined, i. e. has the outer form of a body of least resistance to the flow of gases passing round it. 15 In important draft plants it is further known to employ two fans instead of one, in particular in order to have a spare fan or a second fan available when the action of one fan is to be reinforced. In such case, according 20 to my present invention, the lower part of the two fans is terminated by a curved plate forming a hood which gives the casing of the set of two fans the stream-lined form or form of a body of least resistance to the flow 25 of gases deflected by said hood.

My invention further permits the regulation of the orifice of the two fans by means of a movable ring inside the outlet nozzle common to the two fans, said ring being 30 adapted either to prolong the nozzle or to allow the passage of the gases both inside the ring and between the latter and the nozzle.

A further feature of the invention is that the partition common to the discharge ducts 35 of the two fans is made movable so as to control the connecting of the fans in parallel or the shutting of either fan.

In the appended drawing which shows schematically two embodiments of the invention, Figure 1 is a sectional elevation of a 40 chimney having two inner fans; Figure 2 is a sectional elevation at right angles to Figure 1; Figure 3 is a sectional elevation showing details of the ring and the regulating 45 movable partition or shutter; Figure 4 is a similar view of a modified form of the arrangement when the two fans are placed in two different planes instead of being in the same plane as in Figure 1; Figure 5 is a sectional elevation at right angles to that of 50 Figure 4.

Referring first to Figures 1 and 2, the two fans a a_1 are located inside the chimney on a common median plane, their discharge ducts c c_1 opening into a nozzle d common to both, 55

The casing of the two fans is surrounded, at its lower part, with a curved plate e forming a hood which gives the set of two fans the form designated in aeronautics as the stream lined form or body of least resistance to the 60 flow of gases.

The gases are deflected by said plate to both sides of the set of fans and flow up the chimney with the smallest possible loss of 65 pressure.

The regulation of the gas delivery of the two fans is effected by means of a movable conical ring f shown in Figures 3, 4 and 5, which is provided with any suitable device 70 enabling it to be raised and lowered.

When said ring is in the position shown in full lines, the two fans discharge the fluid in parallel on a total area corresponding to the upper opening of nozzle d . On the contrary, when one of the fans is stopped the 75 ring is raised to the position f_1 shown in dot and stroke lines; the fan that remains in operation discharges on an orifice corresponding to the upper opening of said ring. In the intermediary positions of the ring, the 80 two fans discharge on a total orifice corresponding to an area intermediate the upper openings of ring f and nozzle d .

It is known that the setting of fans in parallel is extremely difficult, as surging between them occurs when they work on a nozzle common to both. In order to avoid this inconvenience the discharge ducts c c_1 of the two fans have a common partition formed by a shutter g (Figure 3) for instance, adapted to rock about a hinge h . According to requirements, to obtain regulation, the shutter g is inclined either to right or to left hand. The end positions g_1 or g_2 of the shutter correspond to stopping of either fan. 90

In the modified form of Figures 4 and 5, the shutter g_4 is in a plane perpendicular to the shutter of Figure 3. The discharge ducts c_4 and c_5 of the two fans are adjacent each other instead of being opposite while the nozzle d , and ring f_4 are the same as in Fig. 3. 100

The regulating ring and movable shutter of Figures 3, 4 and 5 can also be applied to fans placed outside a chimney and blowing atmospheric air into the latter. 105

What I claim is:

1. In combination, a chimney and a draft device associated with said chimney, said draft device comprising a plurality of fans having separate inlets arranged side by side. 110

2. In combination, a chimney, and a draft device associated with said chimney, said draft device comprising a plurality of fans arranged side by side and wholly within 5 said chimney and working in parallel.

3. In combination, a chimney, and a draft device associated with said chimney, said draft device comprising two fans having separate inlets and arranged wholly inside 10 said chimney and spaced therefrom to permit passage of a portion of the combustion gases and adapted to work in parallel and a single curved deflecting plate common to the two fans to form a stream line to the 15 respective fan inlets.

4. In combination, a chimney, and a draft device associated with said chimney, said draft device comprising a plurality of fans having separate inlets and arranged wholly 20 inside of said chimney and being spaced therefrom to permit passage of a portion of the combustion gases and adapted to work in parallel and a single substantial U-shaped 25 deflecting plate common to the several fans and arranged at the ends of the latter presented to the oncoming stream of combustion gases.

5. In combination, a chimney, and a draft device associated with said chimney, said 30 draft device comprising a plurality of fans arranged side by side and each having a separate inlet, and a curved hood partially enveloping the portions of the several casings presented to the flow of combustion 35 gases to form a stream line to the respective fan inlets.

6. In combination, a chimney, and a draft device associated with said chimney, said 40 draft device comprising two fans having separate inlets arranged side by side whereby to draw in parallel a portion only of the combustion gases passing through the chimney, a discharge duct on each fan, a single 45 nozzle common to both discharge ducts, and means for causing said fans to work in parallel, said means comprising a partition

adapted to occupy a variable position between the two ducts to vary the ratio of the passage area of said ducts.

7. In combination, a chimney, a draft 50 device associated with said chimney, said draft device comprising two fans adapted to draw together a portion only of the combustion gases passing through the chimney, said fans being arranged wholly inside the 55 chimney, and the remainder of the gases passing outside of the fans directly up the chimney, a discharge duct for each fan, a nozzle common to the discharge ducts of both fans for inducing the draft of said remainder of gases, and a movable partition between said discharge ducts for varying the ratio of the outlet areas of said ducts, said partition being adapted to be placed in 60 variable positions between total opening and closing of either duct.

8. In combination, a chimney, and a chimney draft device, said draft device comprising two fans adapted to draw together only 70 a portion of the combustion gases passing through the chimney, said fans being arranged wholly inside the chimney and the remainder of said gases passing outside the fans directly up the chimney, a discharge duct for each fan, a nozzle common to the discharge ducts of both fans for inducing the draft of said remainder of the gases, a movable partition between the discharge ducts for varying the ratio of the outlet area 75 of said ducts, and a hood arranged over the lower part of both fans and curved to stream-line them as to a whole to the gases passing outside them.

9. In combination, a chimney, and a draft device associated with said chimney, said draft device comprising a plurality of fans capable of independent or simultaneous operation and each having a permanently open inlet of constant area.

In testimony whereof I affix my signature.

EMILE PRAT.
